Esq.; Harter Secrest & Emery LLP(57) **CLAIM**

The ornamental design for a lighting fixture, as shown and described.

DESCRIPTION

FIG. 1 is a front perspective view of a lighting fixture in accordance with the present invention;

FIG. 2 is a front view thereof, a rear view being a mirror image thereof;

FIG. 3 is a right side view thereof, a left side view being a mirror image thereof;

FIG. 4 is a top view thereof;

FIG. 5 is a bottom view thereof;

FIG. 6 is a front perspective view of an alternative embodiment of the lighting fixture in accordance with the present invention;

FIG. 7 is a front view of the alternative embodiment of the lighting fixture in accordance with the present invention, a rear view being a mirror image thereof;

FIG. 8 is a right side view of the alternative embodiment of the lighting fixture in accordance with the present invention, left side view being a mirror image thereof;

FIG. 9 is a top view of the alternative embodiment of the lighting fixture in accordance with the present invention; and,

FIG. 10 is a bottom view of the alternative embodiment of the lighting fixture in accordance with the present invention. The broken lines shown on the drawings depict portions of the lighting fixture that form no part of the claimed design.
